IRA E. SMITH, OF STOCKTON, CALIFORNIA.

FURNACE THERMOSTAT SWITCH.

Application filed May 26, 1925. Serial No. 32,901.

This invention relates to improvements in electric switches, and particularly to a type to be located in close proximity to a heating furnace, to control the operation 5 of the heating means of the furnace by the heat generated thereby.

This switch is particularly intended to be used in connection with my oil burning system shown in application filed November 10 17, 1924, Serial No. 750,248, but can of course be used for other purposes as well.

The oil burning apparatus in the system mentioned above comprises a rotary burner plate, a motor for driving the plate and for 15 operating a pump to feed oil to the plate; an electric heating element surrounding the plate so that an initial hot zone may be provided adjacent the plate; and electric spark means for igniting the oil when the same 20 is initially fed onto the plate.

In the functioning of these parts, it is desirable that the electric oil-burner heating element shall be heated to a predetermined temperature before the motor is driven, and 25 that the driving of the motor (which causes the oil to be fed to the plate) shall commence simultaneously with the operation of the sparking means.

The oil thus fed to the plate is at once 30 influenced by the heat radiated from the oil burner heating element, and at the same time is subjected to the igniting sparks.

This insures quick ignition of even a low 35 grade of oil, and at the same time prevents any accumulation of unburnt oil on the plate. It is also desirable that when the oil has been properly ignited the spark means shall be discontinued, as its functioning after such time would be merely a 40 waste of current. It is further desirable that these steps shall be carried out automatically and in sequence when definite and predetermined temperatures are successively 45 reached without the presence of an operator being necessary to control the functioning of the different features.

The principal object of my invention therefore is to provide a thermostat switch, so constructed that the above named steps in 50 the operation of the apparatus are caused to automatically take place in proper temperature relation and sequence, as soon as the main circuit of the system is closed.

In general, my device is a combined 55 electrically and oil-flame heated thermostat switch, whose switch-contact actuating member is first heated to a predetermined temperature by electrical means independent of the oil burner, and is so positioned relative to the burner as to be subjected to 60 the direct heat from the burning oil as soon as the latter is ignited, so that the actuating member is then heated to a further degree. The switch contacts opened and closed by the above described heating of 65 the actuating member are so disposed that the above described results are obtained.

The switch is so designed that its operation is controlled solely by variations in 70 temperature, and no time controlled or regulating features enter into its construction.

A further object of the invention is to 75 produce a thermostat switch so constructed that a single model or size of the same will have a very great range of temperature control and adjustment without injury to any part; and which will always be and remain uniform in its operation regardless of extreme variations in temperature. That is, the device will function as well when the 80 temperature is many degrees below zero as it will when 2000° above zero, and at any intermediate temperature.

A third object is to provide a switch so 85 constructed that adjustments may be easily made to enable the different temperatures at which the various steps will take place or stop to be varied at will.

Another object is to provide contact 90 means in the switch so arranged that the motor circuit of the system will be opened when excessive heat is reached in the furnace, said means being also adjustable so that the degree of heat necessary to cause the circuit to be opened may be varied as 95 may be desired.

In connection with the switch features of the device I have provided an air-damper regulator, so that admission of air to the 100 furnace or flue may be automatically and adjustably regulated according to and by reason of temperature conditions in the furnace, so that any predetermined temperature once reached in the furnace may be maintained practically constant.

These objects I accomplish by means of 105

such structure and relative arrangement of parts as will fully appear by a perusal of the following specification and claims.

In the drawings similar characters of reference indicate corresponding parts in the several views:

Fig. 1 is a side view of my thermostat switch, showing the same mounted in connection with a furnace and flue.

10 Fig. 2 is a side elevation of the device detached, partly broken out and in section, the parts being in their normal or cold positions.

15 Fig. 3 is a side view of the contact end of the device, partly in section, showing the contact tube unit moved to open certain ones of the contacts.

20 Fig. 4 is a top plan view of the contact tube assembly and adjacent parts.

25 Fig. 5 is a sectional plan of the adjustable tube supporting unit.

Fig. 6 is a sectional view of an adjacent pair of contact tube holding members.

25 Fig. 7 is a fragmentary top plan view of an adjustable damper-control connection rod.

30 Fig. 8 is a circuit diagram showing one manner in which my switch may be used to control the operation of an oil burning system.

35 Referring now more particularly to the characters of reference on the drawings, the numeral 1 denotes a furnace or fire box in which the oil burner is located, and from which a flue 2 projects upwardly.

40 My thermostat switch structure comprises an expansible tube 3, such as an iron pipe, of considerable length so that a portion thereof may project into the furnace in the zone of direct heat therein, while the remainder of the tube will be outside the furnace. This tube is mounted in a fixed position relative to the furnace by a bracket 4 preferably applied to the same, adjacent its outer end. At said outer end the tube is connected to a casing 5 in which the contact unit hereinafter described is mounted. This end of the tube is open, but the opposite or furnace end is sealed as at 3^a and has fixed therein one end of a non-expansible rod 6 of any suitable composition which projects through the open end of the tube into the casing.

45 This rod is smaller than the bore of the tube so that relative movement therebetween is not hindered. A bearing sleeve 7 is disposed in the tube adjacent the open end thereof to maintain the rod in proper centralized relation to the tube, while allowing of relative sliding movement therebetween.

50 It will therefore be seen that if the tube 3 is subjected to heat it will expand, and acting on the fixed end of the non-expansible rod 6 will cause the latter to be retracted relative to the open end of the tube and casing.

I use this movement, which of course is slight, to operate a multiple switch contact unit in the following manner:

55 Turnably mounted in the casing below the plane of the tube 3 and at right angles thereto is a horizontal shaft 8. A substantially radial and horizontally disposed arm 9 projects outwardly from the shaft and away from the rod 6, while another arm 10 projects upwardly from the shaft and is bent at its upper end to extend toward and abut against the adjacent end of the rod 6.

60 The arm 9 is considerably longer than the arm 10 so that a slight arcuate movement of the outer end of the latter will impart a proportionately greater movement to the arm 9. Spring means 11 between the shaft 8 and the casing acts to rotate the shaft in a direction such that the arm 10 will be maintained in constant engagement with the rod 6. It will therefore be seen that as the rod recedes into the tube when heat is applied to the latter, the arm 10 will follow the movement of the rod, the shaft 8 will be rotated, and the arm 9 will move upwardly.

65 Mounted in transversely opposed relation in the casing above the plane of the tube 6 are brackets 11^a, which support needle bearing spindles 12 parallel to the shaft 8, which in turn support the opposite ends of a tubular unit 13.

70 This unit comprises end members 14 and 15 into which the spindles 12 project, and a plurality of intermediate sleeves 16, independent of each other and of the end members. These sleeves are telescopically fitted together so as to form a rigid unit, the different parts of which are independently turnable relative to each other on a common axis, as shown in Figs. 5 and 6. This axis is of course the spindles 12.

75 The adjacent ends of alternate pairs of the sleeves 16, where they slide into each other, are provided with circular and opposed recesses as shown at 17. These recesses when the sleeves are fitted together, engage and surround glass tubes 18, 19 and 20, the tubes being preferably held centrally of their length. These tubes carry switch contacts as hereinafter seen.

80 Projecting outwardly from the end member 15 and eccentrically located relative to the spindles 12 is a pin 21. This pin is connected to a link 22 which extends to a pivotal connection with the block 23 which is slidably adjustable on the arm 9. By this means when the arm is raised by the rotation of the shaft 8 as previously described, the tube holding unit is rotated likewise, of course altering the angle of setting of the tubes relative to a horizontal plane. By altering the position of the block on the arm 9, the extent of rotation of the tube unit with a given extent of rotation of the shaft 8 may be varied as will be evident.

Onto the end member 14 is fixed one end of a spiral spring 24, the other end of which is secured to the adjacent bracket 11^a. This spring acts against the spring 11, which is 5 the stronger of the two.

The outermost portions of the sleeves 16, on the ends thereof opposite to the recesses 17, have circumferential slots 25 to receive screws 26 which are secured in the telescoped sleeve and end members thereunder. 10

The heads of the screws bite against the outer sleeve portions when tightened down, so that normally all the members will be held together to turn as a unit. It will thus 15 be seen that by loosening different screws, rotatable adjustment of said members relative to each other may be had to any desired extent within reasonable limits. This enables different tubes to be set at different 20 angles relative to each other. Also the setting of all the tubes together or as a unit may be altered by adjusting the members 16 as a unit relative to the end member 15, whose position is fixed when the structure 25 is in normal or cold condition. Likewise the pressure of the spring 24 may be varied by adjusting the end member 14 relative to the other parts of the unit as will be obvious. In this manner resistance of the unit to 30 turning with the rotation of the shaft 8 may be altered to suit different conditions.

The tube 18 carries two sets of contacts 27 and 28 located near opposite ends of the tube. A certain amount of mercury 29 is 35 sealed in the tube, and the latter is set on a slant so that when in a normal or cold position, the mercury will engage contacts 27. These contacts are at that end of the tube which will be raised when the tubes turn 40 with the heating of the tube 3.

In corresponding ends of the tubes 19 and 20, are pairs of contacts 30 and 31 respectively, also normally engaged by mercury 32 in said tubes.

The tube 19 is set on a slope greater than 45 that of the tube 18 but in the same direction, while the tube 20 is set at a considerably greater slope than both the others, and also in the same direction.

All contacts have flexible leads 33 extending therefrom to binding posts 34 mounted on the casing, so that two connections may be made with main circuit wires, without interfering with freedom of movement of 50 the tubes.

Mounted on the tube 3 over a portion thereof outside of the furnace is an electric heating element 35. This is in the form of a jacket completely surrounding the tube, and in turn is covered by a heat insulating jacket 36, so that all heat as developed, will be applied directly to the tube. The circuit 60 to this element is controlled by the contacts 27, but only indirectly and while the leads 37 from this element are connected to cer-

tain ones of the binding posts 34, they are not connected to the corresponding leads 33 of said contacts 27.

In Fig. 8, I have shown a manner in which my switch may be used to control the operation of the major features of my oil burning system. 70

The system includes a rotary burner plate 38, a motor 39 for driving the same and a heating element 40 surrounding the plate. 75 The plate and heating element, which is preferably in the form of a flat strip, are insulated from each other and are so spaced that if interposed in a suitable circuit, a constant train of sparks will jump across 80 the gap therebetween, as shown in my co-pending application filed January 14th, 1925, Serial No. 2,396.

In the operation of this system as set forth in the first mentioned co-pending application, the electric heat functions first, then the spark means and motor start simultaneously, while the electric heater is cut off, and after a certain temperature is reached, the spark is discontinued while the motor of course continues to operate. 85

I use my switch to control these operations in proper sequence, by reason of the heat generated in the following manner:

Referring to Fig. 8, A represents the main power lines with a main switch A¹ therein. A circuit B from the main lines has the contacts 27 interposed therein, as well as a relay 41. Circuit B when closed, also closes, by reason of the relay 41, a circuit C from the main line in which both the electric thermostat heater 35 and the electric burner heater 38 are interposed. Therefore as long as the contacts 27 are closed both electric elements will be heated. Circuit D from the main line has contacts 28 interposed therein, and a relay 42. This circuit when closed, causes a circuit E from the main line to the motor 39 to be also closed, and said circuit will remain closed as long as the contacts 28 are closed. 105

Interposed in the motor circuit E is another relay 43 whose opening is controlled by the opening of the contacts 31, in the circuit F of which said relay 43 is interposed. 110

The sparker circuit G connects the main lines with the plate 38 and the heater element 40 (which are insulated from each other), one lead over said circuit terminating at and being connected to one lead of the motor circuit between the motor and the relay 42. It will therefore be seen that the sparker circuit will not be closed unless the motor circuit is closed at relay 42. 120

It may here be noted that in practice transformers would be interposed in the sparker circuit G, to transform a low to a high voltage current, so that the latter will jump across the gap between the plate 38 and element 40 when said circuit is closed. 125 130

4 A transformer would also be inserted in the heater element circuit C. Such features, however, form no part of the present invention, in which the circuit is shown simply 5 for the purpose of illustration only.

Interposed in that portion of the circuit G which is independent of the motor and heater element leads is a relay 44 which is closed when a circuit H from the main lines 10 and in which the switch contacts 30 are connected, is closed.

In operation when the apparatus is in normal or cold condition the switch contacts 27, 30 and 31 and their respective relay circuits are closed by reason of the slope of the tubes in which said contacts are located, and which causes the mercury in the tubes to engage the contacts.

Relays 41, 43 and 44 are therefore closed, 20 but only circuit C is completed, since relay 42 which controls the complete closure of circuits E and G, is open because contacts 28 are open.

Both electric heater elements 35 and 40 25 will therefore function, but the motor and sparking means will not as yet be operated.

The heater 40 provides only local heat adjacent the burner, not sufficient to materially influence the tube 3 thereabove.

30 The heater 35 however directly applied to said tube supplies sufficient heat to the same to cause its initial expansion. This causes the turning of the tube unit, as previously described, sufficiently to cause the 35 slope of the tube 18 to be reversed relative to a horizontal plane. This allows the mercury therein to flow to the opposite end of the tube leaving contacts 27 and engaging contacts 28.

40 The circuit B is therefore broken, causing the relay 41 to be opened and consequently breaking the heater circuit. At the same time circuit D becomes closed, closing relay 42.

45 Since reversal of the position of the tube 18 has not as yet caused a similar reversal of position of the tubes 19 and 20, owing to the greater initial slope at which the latter are set, relays 43 and 44 are still closed. 50 Hence the motor and sparking circuits will be completely closed, and the motor and spark means will begin to function.

When the motor begins to operate oil is fed to the burner plate and this oil is of course readily ignited by the spark means being initially heated by reason of the hot element 40 surrounding the plate.

55 Heat is then almost instantly generated in the furnace sufficient to effect the tube 3, 60 which now expands to a greater degree than was the case during the operation of the heater 35. As a result the tubes are further turned in the same direction as before until the slope of the tube 19 becomes re-

versed from its original setting, leaving the 65 contacts 30 therein bare.

Circuit H is therefore broken and relay 44 opened, causing the spark circuit to be opened and the spark discontinued. This however does not affect the operation of the 70 motor since the relay 43 is not in the motor circuit, and said circuit will remain closed as long as contacts 28 and 31 and relays 42 and 43 respectively are closed.

75 Now should heat be generated in the furnace to an excessive degree in the event that other fire control devices (not shown in this application) fail to function, the tube 3 will expand to such an extent that the tube 20 will finally be reversed in slope, and the contacts 31 will be left bare.

This will cause the breaking of the circuit F, the opening of relay 43 controlled thereby, and consequently the opening of the motor circuit, causing the motor (which 85 controls the fire) to stop.

To cause the movement of the shaft 8 to operate a pivoted flue air intake damper 45 and open the same from a normal, closed position after a certain heat has been attained in the furnace, I connect an arm 46 to the shaft 8, said arm extending radially of the shaft to a point clear of the casing 5. The outer end of this arm projects into a longitudinal slot 47 in one end of a rod 48, the other end of which is connected to an arm 49 extending radially from the pivot of the damper mounted on the rod 48 adjacent the slot 47, and adjustable longitudinally thereof is a screw 50 alined to engage the arm 46. By adjusting this screw the distance the arm must move along the slot before engaging the screw when moving the arm and consequently opening the damper, may be varied. Therefore different degrees of heat may be raised in the furnace before the damper opens and admits cold air.

Once the damper starts to open its continued opening is of course proportionate to an increase of heat in the furnace.

110 The damper is preferably of counterbalanced type, so that no great force is necessary to operate the same.

This damper arrangement enables hot gases to be maintained in the furnace where they are utilized, instead of a considerable percentage going to waste up the flue. This is because with the operation of the burner a draft is created in the flue which increases with the heat. If air can only be taken in from below the burner, a constant draft of cold air moves past the burner to reach the flue, reducing the effectiveness of the fire and causing a quantity of hot gases to pass up the flue. By means of my arrangement, cold air to supply the necessary amount to the flue is taken in above the burner, and the draft is therefore not felt so much below

the burner. Only sufficient air is then taken in at the latter point to promote proper combustion. The hot gases are therefore retained in the furnace where their heat can be utilized.

From the foregoing description it will be readily seen that I have produced such a device as substantially fulfills the objects of the invention as set forth herein.

10 While this specification sets forth in detail the present and preferred construction of the device, still in practice such deviations from such detail may be resorted to as do not form a departure from the spirit of the 15 invention, as defined by the appended claims.

Having thus described my invention what I claim as new and useful and desire to secure by Letters Patent is:

1. A thermostat switch including a longitudinally expansible tube and a non-expansible rod therein, a rotatable structure mounted in fixed relation with the tube at right angles thereto, a normally closed switch contact structure mounted on the structure and 25 opened by the rotation of said structure, a bell-crank mounted in fixed relation with the tube, one end of said bell-crank engaging one end of the rod, an arm pivoted onto the other end of the bell-crank, a member mounted on the structure and to which the other end of the arm is pivoted in a plane eccentric with the axis of the structure, and means for 30 adjustably clamping the said member with respect to the structure whereby to enable the latter to be rotated without disturbing the said member and parts connected therewith.

2. In a thermostat switch, a plurality of

longitudinally aligned pairs of sleeves, tubes extending at right angles to and between the sleeves of each pair, said tubes containing a quantity of mercury and spaced contacts mounted therein adjacent one end to engage the mercury, means provided with each pair of sleeves for engaging and holding the corresponding tube, means for adjustably rotating each pair of sleeves, and the tube held thereby, relative to adjacent sleeves, axial spindles at the opposite ends of the sleeve structure whereby said structure and the tubes may be rotated as a unit, and 50 thermostatically actuated means for thus rotating said structure.

3. In a thermostat switch, a plurality of longitudinally aligned pairs of sleeves, tubes extending at right angles to and between the sleeves of each pair, said tubes containing a quantity of mercury and spaced contacts mounted therein adjacent one end to engage the mercury, means provided with each pair of sleeves for engaging and holding the corresponding tube, one sleeve of each pair turnably projecting into the adjacent sleeve of the adjacent pair, the latter having a circumferential slot, a set screw mounted in the inner sleeve and projecting 65 through the slot to frictionally engage the outer surface of the slotted sleeve, means for mounting the sleeve structure to enable the same to rotate as a unit, and thermostatically actuated means for thus rotating said structure. 70

In testimony whereof I affix my signature.

IRA E. SMITH.
